(57) **CLAIM**

The ornamental design for a easel, as shown and described.

DESCRIPTION

FIG. 1 is a perspective view of and easel showing my new design.

FIG. 2 is a front elevation view;

FIG. 3 is a right side elevation view;

FIG. 4 is a rear elevation view;

FIG. 5 is a left side elevation view;

FIG. 6 is top plan view;

FIG. 7 is a bottom plan view;

FIG. 8 is a perspective view of the easel plate shown separately for ease of illustration;

FIG. 9 is a perspective view of the easel plate in the folded position, shown separately for ease of illustration;

FIG. 10 is a first end view of the easel plate in a flat position shown separately for ease of illustration;

FIG. 11 is a left side view of the easel plate in a flat position, shown separately for ease of illustration;

FIG. 12 is a top view of the easel plate in a flat position, shown separately for ease of illustration;

FIG. 13 is a right side view of the easel plate in a flat position, shown separately for ease of illustration;

FIG. 14 is a bottom view of the easel plate in a flat position, shown separately for ease of illustration;

FIG. 15 is a second end view of the easel plate in a flat position, shown separately for ease of illustration;

FIG. 16 is a perspective view of the base unit, shown separately for ease of illustration;

FIG. 17 is a perspective view of the base unit in a flat position, shown separately for ease of illustration;

FIG. 18 is a top view of the base unit shown in FIG. 17;

FIG. 19 is a first end view of the base unit shown in FIG. 17;

FIG. 20 is a left side view of the base unit shown in FIG. 17;

FIG. 21 is a second end view of the base unit shown in FIG. 17;

FIG. 22 is a right side view of the base unit shown in FIG. 17; and,

FIG. 23 is a bottom view of the base unit shown in FIG. 17. The broken lines in the drawings are for illustrative purposes only and form no part of the claimed design.
